UNITED STATES PATENT OFFICE.

JAMES L. HUTSON, OF SHELBYVILLE, TENNESSEE.

PERPETUAL CALENDAR.

1,353,751.

Specification of Letters Patent. Patented Sept. 21, 1920.

Application filed January 15, 1919. Serial No. 271,238.

To all whom it may concern:

Be it known that I, JAMES L. HUTSON, a citizen of the United States, and a resident of Shelbyville, in the county of Bedford 5 and State of Tennessee, have invented a new and Improved Perpetual Calendar, of which the following is a full, clear, and exact description.

The object of the invention is to provide 10 a new and improved perpetual calendar adapted to indicate any desired date of either the Julian or Gregorian system. Another object is to permit the user to readily set the calendar for any date of past, present 15 or future years. Another object is to permit the user to readily set the calendar for the present month and to allow of making the desired changes at the end of a month or at the end of a year for the next ensuing 20 month of a year. Another object is to provide a perpetual calendar which is exceedingly simple and durable in construction and not liable to get easily out of order.

With these and other objects in view, the 25 invention consists of certain novel features of construction as hereinafter shown and described and then specifically pointed out in the claims.

A practical embodiment of the invention 30 is represented in the accompanying drawings forming a part of this specification, in which similar characters of reference indicate corresponding parts in all the views.

Figure 1 is a plan view of the perpetual 35 calendar in flat form for use on a desk or similar support;

Fig. 2 is a similar view of the same with the face plate removed;

Fig. 3 is a sectional side elevation of the 40 same on the line 3—3 of Fig. 1;

Fig. 4 is a transverse section of the same on the line 4—4 of Fig. 1.

The perpetual calendar illustrated in Figs. 1, 2, 3 and 4, is mounted on a fixed member 45 100 having a back 101 and a top plate 102, and the back 101 is provided with sidewise extending guideways 103, 104 and 105, in which are mounted to slide sidewise movable members 106, 107 and 108. The movable member 106 is provided on its face with 50 indicating characters 109 representing the "days of the week" arranged one alongside the other and duplicated, as plainly shown in Fig. 2. The movable member 107 is provided with groups of indicating characters 110 disposed in columns and representing

"days of the month," the columns being adapted to register with the columns of the movable member 106. The movable member 108 is provided with groups of indicating characters 111 representing the "names of the months" and disposed in columns adapted to register with the columns of the movable members 106, 107. A single group of indicating characters encompassing seven 60 columns on each of the movable members 106, 107 and 108 is adapted to appear at a time in the opening 112 formed in the face plate 102, as plainly indicated in Fig. 1.

The face plate 102 is provided on its upper side and to the left of the central opening 112 with two groups of indicating characters 115, 116, of which the group 115 represents "centuries of the old or Julian style" and the group 116 represents "centuries of 75 the new style according to the Gregorian system," and the indicating characters appear in columns spaced the same distances apart as the columns of the movable members 106, 107 and 108. The movable member 106 80 is provided on its left-hand side with an indicator 117 extending through a slot 118 formed in the face plate 102 and indicating on any one of the columns containing the indicating characters of the groups 115 and 116. The free end of the indicator 117 is provided with a pin 119 adapted to engage one of a series of apertures 120 formed in the face plate 102 at the corresponding columns of the groups of indicating characters 90 115 and 116.

On the upper face of the face plate 102 and at the right-hand side of the central opening 112 is arranged a group of indicating characters 125 representing the "years 95 in a century" arranged in columns spaced the same distances apart as the other columns containing the indicating characters 109, 110, 111, 115 and 116. An indicator 126 is attached to the right-hand end of the movable member 108 and extends through a slot 127 formed in the face plate 102 below the group of indicating characters 125. The free end of the indicator 126 is provided with a pin 128 adapted to engage any one 100 of a series of apertures 129 formed in the columns containing the indicating characters 125. An indicator 130 is attached to the movable member 107 and appears within the opening 112. The indicator 130 is provided at its free end with a pin 131 adapted 105 to engage any one of a series of apertures 110

132 arranged in the columns containing the indicating characters 111 on the movable member 108. It is understood that the indicators 117, 126 and 130 are preferably made of spring metal to permit of readily engaging their pins 119, 128 and 131 with the apertures 120, 129 and 132, respectively, so as to lock the movable members 106, 107 and 108 in the adjusted positions.

10 In order to set the perpetual calendar for any one month in any year the user shifts the movable members 106, 107 and 108 according to the century, the year in the century and the month of the year. Thus if it is desired to set the calendar say for the month of September, 1918, the user first takes hold of the indicator 117 and moves the same sidewise until the indicator is in register with the column containing the century, that is, in this particular case the first column containing the numeral "19" under the group marked "Centuries, new style." The operator next takes hold of the indicator 126 and moves the same sidewise until it registers with the column of the group of indicating characters 125 containing the year of the century, that is, in the given case "18" which is found in the second column. The user next takes hold of the indicator 130 and moves the same sidewise until it registers with the column of indicating characters 111 representing the month of September, found in the second column, as shown in Fig. 1. It will be seen that the calendar is now set for the month of September, 1918, and in the opening 112 appear the days of the week, the days of this month, and the name of this month at the indicator 130. At the end of the month of September the operator takes hold of the indicator 130 and moves the same to the right to the third column on the indicating member 108 appearing in the opening 112 and having the name "October" thereon. The calendar is now set for the month of October, 1918. At the end of the year the operator takes hold of the indicator 126 and moves the same to the right to the next following column containing the numeral "19" and at the end 50 of the century the operator takes hold of the indicator 117 and shifts the same to the right to the next column containing the numeral "20" under the group of indicating characters marked "Centuries, new style." It will be noticed that the months

of January and February are repeated three times in different columns and sundry appear printed in red to be used with the respective month in leap year. The leap years in the group of characters 125 are also preferably indicated in red in contradistinction to the other years which are printed in black.

Having thus described my invention, I claim as new and desire to secure by Letters Patent:—

1. A perpetual calendar, comprising members movable one relative to the other and provided with separate groups of indicating characters, of which one group represents "old and new style centuries," another group represents "years in a century," another group represents "days of the month," another group represents "days of the week," and another group represents the "names of the months," of the year, the characters in each group being arranged in columns spaced equal distances apart in the several groups, and indicators on the movable members, and of which one is attached to the member having the "days of the week" and indicates on the "centuries," another is attached to the member having the "names of the months" and indicates on the "years in a century" and another is attached to the member having the "days of the month" and indicates on the "names of the months."

2. A perpetual calendar, comprising a fixed member having an opening and provided with groups of indicating characters representing "old and new centuries" and "years in a century," movable members held movably on the said fixed member independent one of the other, one of the movable members having groups of indicating characters representing the "days of the week" and having an indicator indicating on the said "old and new style centuries," another of the movable members having groups of indicating characters representing the "names of the month" and having an indicator indicating on the "years of a century" and another of the said movable members having groups of indicating characters representing the "days of the month" and having an indicator indicating on the said "names of the month," each group of indicating characters of the movable members being adapted to appear in the said opening.

JAMES L. HUTSON.
